UNITED STATES PATENT OFFICE

HOMER A. EVANS, OF COLUMBUS, OHIO

DRAFT CONTROL FOR TUNNEL KILNS

Application filed October 28, 1930. Serial No. 491,793.

In the drawings:

Figure 1 is a top plan view of the exit end of my improved kiln.

Figure 1a is a similar view of the entrance end of the kiln.

Figure 2 is a side elevation of the exit end of the kiln.

Figure 2a is a side elevation of the entrance end of the kiln.

Figure 3 is an enlarged detail view.

Figure 4 is a detail vertical longitudinal section of the kiln.

Figures 5 and 6 are longitudinal vertical sectional views of a kiln showing, by arrows, the natural and the artificial drafts, respectively, in the kiln.

The primary object of my invention is to provide, in a kiln having a heating up zone, one or more high temperature zones, and a cooling zone, through which zones ware travels, means for introducing an air blast in the tunnel toward the entrance end of the tunnel or kiln, so that the natural draft, which travels from the entrance end of the kiln through said zones, and toward the exit end of the kiln, is nullified and the temperature developed in the high temperature zones is prevented from traveling toward the exit end of the kiln; and with this, and other objects in view, my invention consists of the parts, and combination of parts, herein described.

The reference numeral 1 designates a tunnel kiln embodying my invention; the numeral 2 designates the entrance end of the kiln, and the numeral 3 the exit end of the kiln.

Near (preferably) the exit end of the kiln I position a blower 4 of suitable capacity to create the necessary or desirable blast of air, which I utilize, as hereinafter described, to nullify the natural draft of the kiln. A pipe or conduit 5 extends from the blower 4 alongside of the kiln to a point near the entrance end of the kiln. At intervals throughout the length of the conduit 5 I run branch pipes 6 therefrom into the kiln tunnel, said branch pipes being provided with suitable control valves 8, whereby a blast of air may be introduced from below, or at the sides, or above the

vehicles carrying the ware under treatment. At the exit end of the tunnel a branch pipe 10 leads from the conduit 5 and is provided with nozzle 11 projecting at a higher level than the pipes into the exit end of the tunnel, the pipe 10 being provided with a control valve 12. By means of the valve on each of the branch pipes, I can readily control the entrance of the blast to the desired or necessary point in the tunnel.

The high temperature zones are provided with muffle walls 13. The stack 15 is near the entrance end of the tunnel.

A blast of air from below, or at the sides of the vehicle carrying the ware through the tunnel, is projected into the tunnel from the branch pipes 6 into the currents of air (see arrows 16) induced by the blast from pipe 10 toward the stack near the entrance end of the tunnel. This acts as a counter draft and damper to the natural draft, indicated by the arrows 14, and accelerates the artificial draft (arrows 16) and causes the heat to bank up within a limited area immediately preceding the point of entrance of said draft of air and toward the entrance.

By my invention I draw the heat radiated from the ware and conveyors in the cooling end of the tunnel through the high temperature zone toward the entrance end of the tunnel so that all heat not lost by radiation passes over or amidst the ware being heated up, in the heating section, thus conserving heat. The amount of draft provided will control the rate at which the hot air will travel toward the entrance end of the tunnel.

What I claim is:

1. In a tunnel kiln having a heating up zone, one or more high temperature zones, and a cooling zone through which the ware travels, an injector arranged at the exit end of the tunnel for introducing a blast of air thereinto for travel toward the inlet end of the tunnel, injectors arranged at intervals in the length of the tunnel for injecting blasts of air supplementing the first-named blast, whereby blasts of air counter to the natural draft of the tunnel are produced to substantially nullify such draft, and means for inde-

pendently controlling the blasts through said injectors.

2. In a tunnel having a heating up zone, one or more high temperature zones, and a cooling zone through which the ware travels, a blast device arranged for introducing a blast of air into the tunnel at its exit end for travel toward its inlet end, a plurality of blast devices arranged at intervals along the length of the tunnel for introducing thereinto blasts of air supplementary to the first-named blast of air, said blasts of air operating to introduce a draft current in opposition to the natural draft current, whereby said natural draft current is substantially neutralized, and valves for independently controlling the flow of air through said blast devices.

In testimony whereof I affix my signature.
HOMER A. EVANS.
